UNITED STATES PATENT OFFICE

2,146,416

SPRAY GUN NOZZLE

Svend Bramsen and Fred W. Wahlin, Chicago, Ill., assignors to Binks Manufacturing Company, Chicago, Ill., a corporation of Delaware

Original application October 31, 1935, Serial No. 47,580. Divided and this application November 8, 1937, Serial No. 173,365

13 Claims. (Cl. 299—140.1)

Our invention relates to novel structural features of a spray gun and in general aims to accomplish the following objects:

(1) Providing improved rearward guide and adjustable pressure provisions for the needle valve which controls the discharge of material from the material nozzle, to prevent this valve from binding if the valve is not exactly straight or if the forward and rearward guides are not in exact axial alignment.

(2) Providing a mounting for the said rearward guide and adjustable pressure provisions associated with the needle valve which will permit the major parts of this assemblage to be attached to, and detached from, the gun body as a unit.

(3) Providing simple and effective means for transmitting digital pressure on the trigger of the gun to the needle valve, and for preventing dust from entering operative portions of this rearward guide.

(4) Providing an effective head and seat for the supplemental air valve which controls the supply of spray-flattening air to the side ports of the air nozzle, and an effective guide for this valve head.

(5) Providing a duplex seating of the material nozzle on longitudinally spaced portions of the head of the gun body to insure an exact alignment of this nozzle with the said head, as well as an airtight seating of this nozzle on the gun head, even if the threaded connection of this nozzle to the said body head is not perfectly accurate and right.

(6) Providing air passageways in a forward body part of the gun for affording an ample air supply to longitudinal air passages in the air nozzle of the gun.

(7) Providing effective means whereby the attaching ring interposed between the air nozzle and the gun body will permit an accurately axial seating of this air nozzle on the material nozzle even if the threaded connection of the said ring to the gun body is not exactly coaxial with the material nozzle.

(8) Providing simple means for stiffening a tubular frontal part of the gun into which the material nozzle is threaded, and utilizing the said means for distributing air to numerous longitudinal air passages formed in the material nozzle.

(9) Providing simple, durable and easily replaceable means for reducing wear on the parts of the trigger of the gun which respectively engage the stem of the main air valve and a pres-

sure-transmitting member associated with the needle valve.

Illustrative of the manner in which we accomplish the above recited objects.

Fig. 1 is a central, vertical and longitudinal section through a spray gun embodying our invention, with the usual suspension hook and the major portion of both the handle and the trigger of the gun broken away.

Figure 2 is an enlargement of the forward portion of Fig. 1.

Fig. 3 is a similar enlargement of the forward part of the gun body alone.

Fig. 4 is a further enlargement of an upper portion of Fig. 1, showing the means which seal the forward end of the attaching ring to the air nozzle while permitting a rocking of the ring with respect to the said nozzle.

Fig. 5 is a side elevation of the material nozzle, and Fig. 6 a rear elevation of the same nozzle.

Fig. 7 is a fragmentary enlargement of a considerable portion of Fig. 1, drawn on the same scale as Fig. 2.

Fig. 8 is a fragmentary and enlarged section taken along the line 8—8 of Fig. 7 through the trigger and parts adjacent thereto.

Fig. 9 is a similarly enlarged rear perspective view of the presser plate attached to the main part of the trigger.

Fig. 10 is an elevation of the rearward portion of the material-discharge controlling needle valve, the presser member threaded on this valve, and the cap-nut which latches the presser member in its adjusted position, drawn on the same scale as Fig. 7.

Fig. 11 is an elevation of the unitarily detachable assembly of parts of the control unit associated with the needle valve.

Fig. 12 is a rear elevation of the portions of the gun, shown in Fig. 1.

Fig. 13 is a front elevation of the forward gun body part which is separately shown in section in Fig. 3, drawn on the same scale as Fig. 1.

Fig. 14 is an enlarged radial section of a portion of the front end of the slideable thrust sleeve through which pressure on the trigger of the gun is transmitted to the presser member on the needle valve.

Fig. 15 is a central and longitudinal section through the adjusting tube and the parts carried thereby, showing this assemblage when the tube has been detached from the gun body to permit an adjusting of the effective length of the needle valve.

In the illustrated embodiment, the main body

part of our gun includes a barrel or stock **S** having the usual longitudinal main air passage **M**, a tail portion **23** (Fig. 12) depending from the rearward portion of this stock, and a handle **H** depending from this tail portion. The companion forward body part **F**, shown almost completely in section in Fig. 3, has a flat rear face portion **f** bearing against the flat forward end of the stock, and the forward body part also has a rearwardly projecting boss **B** extending through a longitudinal bore in a lug **L** depending from the forward end of the said stock.

A doubly threaded nipple **N** clamps the forward body part tightly against the main body part, after the manner more fully described in our Patent No. 2,107,726, issued Feb. 8, 1938 on a Spray gun.

The forward portion of this nipple is threaded into the rearward portion **1a** of an air bore **1** from which a passage **2** leads forwardly to a forwardly open annular channel **3** formed in the radially outward frontal portion of the forward body part, as shown in Figs. 3 and 13. This forward body part also has a deeper forwardly open channel **4** concentric with and radially inward of the channel **3**, into which channel **4** the air bore **1** also opens; and the body portion within the inner wall of the deeper channel **4** has an axial bore **5a** forming the forward arm of an elbowed material passage **6**, which passage has its inlet in a tubular shank **7** depending from the main portion of the forward body part.

The said axial bore **5a** has its forward portion provided with a non-tapering thread **5b** and also has a more rearward and rearwardly tapering bore portion **5c**, and the portion of the forward body part in which the said axial bore **5a** is formed has its forward end spaced rearwardly from the front face of the radially outward portion of this body part in which the outer annular channel **3** is formed. Moreover, the outer wall of the inner channel **4** has a portion **4a** flaring forwardly and preferably in the same conical surface with the said tapering portion **5c** of the axial bore in the frontal body part.

This alining of two peripheral, longitudinally spaced and coaxial portions of the frontal body part of our gun permits the said portions **4a** and **5c** to afford zone-like annular seats respectively for a midlength peripheral portion **8a** and a rear end peripheral portion **8b** of the material nozzle of our gun (shown separately in Figs. 5 and 6) when the said nozzle portions present their peripheries in a conical surface of the same cone angle **8** (Fig. 5) as that in which the tapering portions **4a** and **5c** were bored. Moreover, the longitudinal spacing between each set of these tapering portions permits a non-tapering threaded portion **8c** of the material nozzle to be screwed into the similarly threaded portion **5b** of the frontal body part.

With the previous construction of such spray appliances, the disposition of the axis of the material nozzle with respect to the body part which supports this nozzle, varied according to the extent to which the thread on the nozzle approached an exact alining with the axis of the nozzle, and also on the accuracy with which the corresponding bore in the gun body was threaded. And, since the thread on the nozzle was usually on the extreme rearward portion of the shank of the nozzle, a departure from the intended axial alinement of this nozzle with the corresponding air nozzle of the gun was often

magnified to such an extent at the front of these nozzles as to dispose the outlet tip of the material nozzle decidedly eccentric to the central port of the air nozzle, thereby producing a correspondingly distorted pattern of the projected spray.

With our here presented arrangement, the annular tapering seats **4a** and **5c** in the forward body part can readily be formed in a single operation with a boring tool which has corresponding portions accurately ground to the desired common taper angle, and the annular surfaces **8a** and **8b** on the material nozzle can both be ground accurately and by a single operation to the same common taper angle. Consequently, the straight-threaded connection between the nozzle shank portion **8c** and the body bore portion **5b** can be sufficiently loose to permit both of the said nozzle surfaces to seat firmly and to insure an exact positioning of the nozzle. This allows also for manufacturing variations in the non-tapering threadedly interconnected parts, so as to insure an equally proper supporting of material nozzles which have been made at different times.

The companion air nozzle **10** is desirably of a cap type, bored to fit upon a forwardly tapering frustro-conical portion **8d** of the material nozzle which is forward of the oppositely tapering portion **8**; and the air nozzle has the usual central air port **p** into which the usual tubular tip **8t** of the material nozzle freely extends, as well as the usual peripheral head **10b**. This nozzle is clamped rearwardly on the material nozzle by a retaining ring **11** which has its rear end portions screwed upon a peripheral thread **5d** on the forward end of the forward body part, the forward end of which ring presents an interior annular flange **11a** in front of the bead **10b** on the air nozzle.

To compensate for manufacturing variations in the fit of the retaining ring on the forward body part, to seal the retaining ring adequately to the air nozzle, we interpose a metal gasket **12** (desirably of bronze) between the interior flange **11a** of the retaining ring and the front of the bead **10b** on the air nozzle. We also preferably form the rearward portion of the bore of this flange so as to flare rearwardly and to present a rearwardly concaved annular face shaped as a zone of a spherical surface which has its center point approximately at the apex **50** (Fig. 2) of the conical surface of which the annular nozzle seats **4a** and **5c** form a part, and form the gasket **12** of an approximately quarter-circular section presenting a curved section to the said interior flange and presenting a flat rear face to the peripheral flange **10b** on the air nozzle.

In addition, we preferably provide a second interior flange **11b** on the retaining ring, somewhat rearward of its said end flange **11a**, this second flange having its bore diameter intermediate that of the bores of the aforesaid flanges **11a** and **10b**.

With the parts thus constructed, the gasket **12** can readily be snapped into the forward portion of the retaining ring from the rear of that ring, so as to be held in the latter by the rearward flange **11b** when the retaining ring is detached. When this retaining ring and gasket assembly **10** is slipped over the air nozzle (after the latter has been socketed on the material nozzle as in Figs. 1 and 2) the interengaging sphere-zone surfaces of the flange on the retaining ring and of the gasket permit the retaining ring to rock on

the air nozzle during the screwing of the retaining ring on the gun body, so as to compensate for any inaccuracy in the threaded connection provided for that purpose, and the gasket thereafter seals the forward end of the retaining ring to the air nozzle.

In the material nozzle, the tip portion $8t$ extends sufficiently forward beyond the forwardly tapering portion $8d$ to afford an air space 14 behind and adjacent to the usually flat central forward part (or cap end) $10a$ of the air nozzle, and the material nozzle has a plurality of circumferentially spaced longitudinal passages $8e$ leading to this space. In addition, the material nozzle preferably also has an annular groove $8h$ in its rear end, from which the said passages lead. This groove faces the inner annular channel 4 in the front end of the gun body, to which air is supplied through the air bore 1 in that body, so that this groove co-operates with the said channel in distributing air to the said passages.

To equalize this air distribution we dispose an annular baffle of smaller area (in a plane at right angles to the axis of channel) in the said channel 4 and preferably in the forward portion of this channel, so as to cause the air to flow circumferentially to a considerable extent before reaching the mouth end of the channel.

For this purpose we preferably employ a metal baffle ring 15 press-fitted on the tubular body portion which has the interior thread $5b$, this ring preferably being considerably wider than its maximum thickness and preferably decreases in thickness rearwardly, from a maximum thickness somewhat less than the width of the annular channel 4 in which the said ring is located.

Thus disposed, the baffle ring 15 also serves the important purpose of stiffening the tubular body portion on which it is mounted, to permit that body portion to be accurately bored without danger of cracking it, even when the thickness of the tube wall is rather small so as to reduce the diameter of the head portion of the forward body part.

When the air nozzle is to effect a flattening of the spray, the rearwardly tapering portion 8 of the material nozzle preferably is of such length as to extend forwardly for a considerable distance beyond the front end of the gun body, and this tapering portion is spaced from the rear end of the forwardly tapering portion $8d$ by a peripheral groove disposed adjacent to the rear end of the air nozzle. This permits air admitted from the outer annular body channel 3 to the annular space between the front end of the gun body and the rear end of the air nozzle to flow through longitudinal passages 17 in the rear end part to the air nozzle for reaching the side air passages 18 of that nozzle.

The side air for this purpose is supplied (after the manner more fully described in our Patent No. 2,107,726, issued Feb. 8, 1938) from the main air passage M through the inlet bore 1 and a port P leading forwardly from the latter, this port being controlled by the head V^1 of a side-air control valve V which can be adjusted by a rearward knob V^3 .

Moreover, we preferably construct our material nozzle so that the rear end of the air nozzle will be spaced forwardly from the doubly channeled forward end of the gun body (by a space 46) when the air nozzle seats on the material nozzle, so that this space around the material nozzle will co-operate with the outer channel 3

in equalizing the air distribution to the side air passages 18 of the air nozzle.

To control the discharge of material from the material nozzle, we employ a simple rod-like needle valve 13 extending rearward axially through the body boss B , and through an annular packing 19 disposed in a rearwardly open bore in the said boss. This packing is compressed around the needle valve by a plunger or gland 20 which slidably fits the rearward portion of the said bore in the body boss and which gland is fastened to the head of a stuffing box cap 21 threaded on the rear end of the said boss B . To effect this fastening, which permits the gland to be detached along with the stuffing box cap 21 we form the gland with a diametrically rearward extension $20a$ which extends through and is flared out into a rearwardly flaring axial bore in the head of the said cap, as shown in Fig. 2.

Moreover, the axial bore $20b$ of the gland 20 of the forward gun body part is preferably somewhat larger in diameter than the needle valve, so as to avoid any cramping of this valve. Then we also provide the following novel arrangement in the more rearward part of our spray gun for guiding the needle valve in such a manner as to avoid any binding or cramping of that valve, while permitting the needed adjustments and also facilitating a disassembling of the control provisions associated with that valve.

The pivoted trigger T of the spray gun depends in the usual manner in front of the handle H and of the usual tail portion 23 which connects the stock S to this handle, and the said tail portion has a bore 24 coaxial with the needle-valve-guiding bore 22 in the forward body part and with the material nozzle. Mounted in this bore is a sleeve (Fig. 11) which has a portion 25 fitting the rear end of the said bore, a mid-length portion $25a$ threaded into that bore and a peripheral flange $25b$ normally bearing against the rear end of the body tail portion 23 .

The more forward portion of this sleeve presents a peripheral flange $25c$ behind a contraction $24a$ of the bore 24 , which flange is sealed to the shoulder affording that contraction by a gasket 26 as shown in Fig. 7. In addition, the sleeve has a cylindrical portion $25d$ fitting into the said bore contraction $24a$, and the sleeve extends forwardly through the latter to present its forward end portion $25h$ in front of the adjacent portion of the tail 23 . Threaded on this portion $25h$ is a retainer ring 28 which bears rearwardly against the said tail portion and which also clamps the radially outer portions of two annular wipers 27 against the front end of forward sleeve portion $25h$ while permitting the radially inward portions of the wipers to flare away from each other longitudinally of the said sleeve.

The part of the said sleeve forward of its mid-length threaded portion $25a$ has a bore 30 considerably larger in diameter than the needle valve 13 , through which bore a presser tube 31 slidably extends. This tube has an annular head 32 clinched to it as shown in Fig. 14, and has the wipers 27 fitting against it to prevent dust from entering the sleeve bore 30 to interfere with a free sliding of the presser tube in that bore.

The needle valve extends rearwardly through the bore of the tube 31 , and thereafter threadedly through a presser head 33 behind that tube and into a long cap nut 34 which normally locks the presser head to the needle valve. Bearing forwardly against this presser head and housing the

forward portion of the said cap nut is a ring 35, which freely houses the forward portion of the cap nut 34. This ring is slideable in the bore of an adjusting tube 36 which has a midlength part threaded into the rearward portion of the bore of the sleeve 25. The rear end of the adjusting tube is normally closed by a cap 37, which cap has its rear end portion 36b enlarged and peripherally knurled, and a compression spring 38 interposed between the said cap 37 and the slideable ring 35 continually presses the said ring forwardly.

If the bore of the slideable ring 35 were slidably fitted upon the cap nut 34, this interfitting would hold the adjacent part of the needle valve coaxial with the guide sleeve 36. Consequently, any deviation from an exact axial straightness of the needle valve, such as frequently occurs owing to a bending of such valves while they are being hardened, would cause the heretofore frequently encountered cramping (and even sticking) of this valve which interferes with the normal operation of the gun. But with the bore of the ring 35 suitably larger than the diameter of the cap nut portion housed by it, we accomplish the following result:

When the adjusting tube 36 is unscrewed from the sleeve 25, this tube (together with the spring 38, the presser ring 35 and the cap 37) are detached as a unit, as shown in Fig. 15, this being permitted by making the bore 36c in the forward end of that tube larger in diameter than the head 33a of the presser head 33. The needle valve, with this presser head and the locknut 34 still mounted on it, as in Fig. 10, can then be slid manually rearward for adjusting the position of the presser head on this valve.

To insure a substantial axial rearward pressure of the trigger on the frontal head 32 of the presser tube, we provide the trigger proper (T) with a flat rear portion face T² extending in front of both the said tube head and the usual stem 42 on the air valve 40, and also provide the trigger proper with a flat upwardly facing shoulder at the lower end of the said flat rear face portion.

Then we provide a presser plate 43, shaped as in Fig. 9, which is preferably of hardened steel while the trigger may be of aluminum alloy. This presser plate has a lower flat end and has a forked upper portion presenting two fork fingers 43a, spaced by a distance greater than the diameter of the needle valve 13, so that the said valve can extend freely between them. These fingers 43a have their rear faces formed as portions of a common cylindrical surface having a horizontal axis intersecting the axis of the needle valve. When this presser plate is positioned against the said flat face portion of the main trigger portion with the lower end of the plate bearing against the shoulder T¹, a single screw 44, desirably clinched to the trigger proper, suffices for fastening it rigidly to the latter. Then when the trigger is retracted, the rear faces of the plate prongs 43a bear simultaneously against the tube head 32 substantially on a line diametric of that head, so as to effect an axial thrust on the slideable tube 31.

By using the above described features conjointly in a spray gun, we obtain the following advantages over the now commercial guns:

(1) A generally straight path of the air flow through the air inlet 1 of the forward body part and from the latter both through the longitudinal air passages in the material nozzle and to the side air passages of the air nozzle.

(2) A tightly sealed and firm mounting of the material nozzle, regardless of the fit of the threads on the shank of that nozzle.

(3) A circumferential distribution of the air behind and around the material nozzle through channels and chambers of ample size.

(4) A positive alining of the air nozzle with the material nozzle regardless of a possibly inaccurate fitting of the threaded connection between the retaining ring 11 and the forward end 10 of the body.

(5) A speedy replacing of the packing 18 around the needle valve, effected by having the plunger or gland 19 fastened to the cap 21.

(6) A rearward guiding of the needle valve which automatically adjusts itself to any lack of an axial straightness of that valve.

(7) A transmitting of the trigger pressure to a part of the needle valve far behind the trigger, so as to leave that valve free between the presser member 33 and the forward guide bore 22.

(8) Preventing dust from interfering with a free sliding of the presser tube 31, which we accomplish by the wipers 27.

(9) Insuring a non-tilting longitudinal thrust on this presser tube, by providing it with an enlarged forward head engageable by the convexed finger portions 43a of the presser plate on the trigger.

(10) Guarding against a tampering with the needle valve adjustment. Since the cap 37 of the adjusting tube 36 has a smooth rear head, as shown in Fig. 12, the interior screw-driver receiving slot 37a on this cap is not exposed for tempting an inexperienced gun user to turn this cap.

However, we do not wish to be limited to the conjoint use of the here disclosed features of our invention, or to the heretofore described desirable details of construction and arrangement,—as for example, to the use of the two-piece air nozzle member constituted by the air nozzle and the retainer ring—since many changes could obviously be made without departing either from the spirit of our invention or from the appended claims.

This is a division of our copending application Ser. No. 47,580, filed October 31, 1935, now Patent No. 2,102,303, issued Dec. 14, 1937, for Spray gun valve.

We claim as our invention:

1. In a spray gun, a gun body having its front end formed to present a tubular portion surrounded by an annular and forwardly open channel coaxial with the said tubular portion, and having a material passage and an air passage leading respectively to the bore of the said tubular portion and to the said channel, the outer wall of the said channel having its forward portion flaring forwardly; a material nozzle having a tubular shank the rearward portion of which is socketed in the said bore, and having a rearwardly tapering exterior portion seated on the said flaring portion of the outer channel wall; the said material nozzle having longitudinal air passageways communication with the said channel.

2. In a spray gun, a gun body and material nozzle assemblage as per claim 1, in which the said flaring channel wall portion is farther forward than the front end of the said tubular body portion.

3. In a spray gun, an assemblage as per claim 1, in which the shank of the material nozzle is threaded into a part of the bore of the tubular

portion, and in which the said bore and the said shank have tightly interfitting parts disposed rearwardly of the threading of the said shank into the said bore.

5 4. In a spray gun, an assemblage as per claim 1, in which the shank of the material nozzle has a rearwardly tapering exteriorly frusto-conical rear end portion; and in which the said bore has a portion thereof formed to afford a seat 10 engaged by the said rear end portion of the shank of the material nozzle.

5 5. In a spray gun, an assemblage as per claim 1, in which the shank of the material nozzle has a rearwardly tapering frusto-conical exterior portion; and in which the said bore has a portion thereof formed to afford an annular seat engaged by the said tapering portion of the shank of the material nozzle, the said seat and the said flaring portion of the outer channel wall being formed 15 as parts of a common conical surface.

20 6. In a spray gun, an assemblage as per claim 1, including a ring fitted upon the said tubular portion of the gun body and disposed within the said channel, the ring being of less thickness than the width of the said channel and serving as a baffle 25 for distributing air circumferentially of the channel to the said air passageways in the material nozzle.

20 7. In a spray gun, an assemblage as per claim 1, including a ring sleeved upon the forward end of the said tubular portion of the gun body, the said ring decreasing rearwardly in thickness and has its maximum thickness appreciably less than the radial width of the said channel.

30 8. In a spray gun, an assemblage as per claim 1, including an annular baffle disposed in the said channel and supported by a wall of that channel, the said baffle being of smaller area, in a section at right angles to the axis of the said channel, than the cross-sectional area of the channel.

35 9. In a spray gun, a body having its front end provided with a central and forwardly open bored part and having two forwardly open channeled parts concentric with the said bore; the body also having an interior air chamber opening into the inner channel and having a port connecting said air chamber to the inner channel; a material nozzle having its rear end portion socketed in said bored part and having a peripheral portion, intermediate of the ends of the said nozzle, seated on a forward part of the said body between the two channels of the channeled parts, said nozzle having longitudinal air passages open at their rear toward the inner of the said channels;

40 and an air nozzle member fitted both upon a part of the material nozzle forward of said peripheral portion of the latter and upon the periphery of the said forward body end; the air nozzle member having side air passages extending through it, and being formed to afford an annular air

chamber in front of the outer of the said channels, from which air chamber the side air passages lead.

10 10. In a spray gun, a gun body including a forward part presenting a forwardly opening tubular portion and two forwardly open concentric channeled portions surrounding said tubular portion, the said body part having an air chamber connected to both of the said channels; a material nozzle having a shank socketed in the bore 10 of the said tubular portion and having a larger diameter nozzle portion seating against an annular portion of said body part between the two concentric channels, the said nozzle having longitudinal air passages leading from the channel of the inner of said channeled portions; and an air nozzle member fitted upon the material nozzle and having air passages disposed for receiving air from the channel of the outer of said channeled portions.

15 11. In a spray gun, a gun body comprising a forward portion having a forward opening bored part, a forward opening channeled part surrounding said bored part to provide a channel therebetween, and provided with an air supply 25 passage communicating with the channel of the channeled part, said channeled part having a rearwardly tapered annular seat, said bored part having a threaded portion and having a rearwardly tapered annular seat rearwardly of said 30 threaded portion; a nozzle element comprising axially spaced frusto-conical and rearwardly tapered seating portions respectively seating on said seats of said channeled and bored parts, and having intermediately said frusto-conical portions a threaded portion for engagement with the threaded portion of said bored part to coaxially seat said tapered portions, said nozzle element being provided with a material passage leading from said bored part and air passages leading 35 from said channeled part, said seating portions being in a common conical surface.

40 12. In a spray gun as characterized in claim 11, and in which the nozzle element has a forwardly tapered portion, a side port air nozzle member having a rearwardly flared portion formed to seat upon said forwardly tapered portion of said nozzle element, and a retainer connected to said air nozzle member and to the forward portion of said gun body for seating said air nozzle member on said forwardly tapered portion of said nozzle element.

45 13. A spray gun as specified in claim 10, in which said material nozzle has a rearwardly open annular groove which communicates with said longitudinal air passages and also with the channel of the inner of said channeled portions for direct passage of air.

50 SVEND BRAMSEN.
FRED W. WAHLIN.
